UNITED STATES PATENT OFFICE

ARTHUR JAMES MOXHAM, OF LOUISVILLE, KENTUCKY.

IMPROVEMENT IN FARE-BOXES.

Specification forming part of Letters Patent No. 149,671, dated April 14, 1874; application filed December 3, 1873.

To all whom it may concern:

Be it known that I, ARTHUR J. MOXHAM, of the city of Louisville, in the county of Jefferson and State of Kentucky, have invented an Improvement in Passenger Fare-Boxes, of which the following is a specification:

This invention relates to a class of registering fare-boxes; and consists, generally, of the combination, in a fare-box, of a receiving with a recording mechanism, all of which will be specially and fully hereinafter described. The object of this invention is twofold—first, to provide an efficient means of causing passengers, or persons in any traveling conveyance or assembly, to deposit in a fare-box the fare or money which may be justly due by them, by causing a gong, actuated by suitable mechanism, to announce the fact of the deposit of the fare after such deposit has been made; and, secondly, coincidently with the sounding of the gong, to cause a suitable mechanism to record on a dial the number of fares paid or persons depositing fare in the box during any certain time. Any failure to deposit fare in the box will thus be rendered obvious to the person in charge of the box, and to other persons or passengers, by the failure of the gong to sound; and the abstraction of fare from the box, or the tampering with the mechanism thereof by any unauthorized person, can thus be readily detected by those to whose custody the box is intrusted for the purpose of collecting or noting its contents, by observing either the action or non-action of the recording mechanism.

In order to accomplish the object above mentioned, I construct my fare-box as follows, premising that it is intended for the collection of metal coins of lawful money—such as nickel coins, for instance—or for tokens representing certain values received, and made of sufficiently hard and durable materials to actuate the receiving mechanism of the box. The box itself, as a whole, may be made of any suitable metal, or of wood, or partly of wood and partly of metal, and having glass inserted in such parts as may be desired, for the purpose of inspecting portions of its interior.

In the drawing forming part of this specification, Figure 1 is a perspective view of the exterior of the fare-box. Fig. 2 is a vertical

section of the box in a central plane from front to rear. Fig. 3 is a vertical section in a central plane, at right angles to the section shown in Fig. 2, of a modified form of the fare-box, showing two fare-chambers, duplicates of each other, and also showing a section through a lamp-chamber attached to the box. Fig. 4 is a perspective view of a part of the receiving mechanism detached from the box. Fig. 5 is a geometrical view, partly in section, of a part of the receiving mechanism detached from the box. Fig. 6 is a section through the final lock-chamber, showing a modification of the method shown in Fig. 3 of locking the bottom of the chamber. Fig. 7 is a perspective view of a modification of the receiving mechanism shown in the preceding figures. Fig. 8 is a section in a central plane from front to rear through the final lock-chamber and lower part of the fare-box, which terminates in a spout or pipe.

In these figures, A is a mouth-piece in the top of the fare-box for the reception of coins. It is perforated with an orifice, *a*, the slotted part of which is adapted for the insertion of a coin. The mouth-piece A, instead of being secured to the top of the box as a separate piece, may be dispensed with, and the orifice *a* may be made in the top itself, which will then become the mouth-piece. B is a hinged slide, provided with a spring at *b*. C is a stationary guide at right angles to the slotted part of the orifice *a*, having a recess, *c*, in its lower edge, and an offset, *c*², upon one side, so that this recess and offset form, in conjunction with spring-slide B, a slot through which the coin can pass. This offset *c*² may be placed upon the side or sides of slide B, instead of upon guide C, where it will perform a similar function. The slide B may also be made stationary, and the guide C hinged and movable against a spring, as seen in Fig. 7, when their combination in this manner will effect a result similar to that effected when combined as shown in the preceding figures—that is, when a coin is pressed against the guide C it will be tripped against the edge of slide B as a fulcrum by the reaction of the guide C, and discharged into a receptacle below. D is a hinged catch, provided with a spring at *d*. One arm of this catch serves to contract or to give a varying length to the slotted part of the orifice

a, and its other arm serves as a stop to limit the depression of spring-slide *B*. It will be observed that this catch *D* also serves another purpose: If its arm in the slotted part of orifice *a* be moved in its line of angular motion without pressure being directly applied to slide *B*, the catch itself will actuate the mechanism of the fare-box through the medium of slide *B*, which it will depress if its arm in the slotted part of orifice *a* be made of a certain length or be depressed low enough. But this arm may be made of such configuration as to move in its line of angular motion clear of slide *B*, and thus not actuate the recording mechanism by any motion of its own. The office of the catch *D* is, therefore, threefold: First, it will prevent the slide *B* from moving or actuating the registering mechanism, unless the catch itself is either first or simultaneously moved with the slide *B*; second, if moved independently of slide *B* by the insertion of an improper coin, token, or instrument, it can depress the slide only sufficiently to cause its depression to be registered upon the dial, and thus make manifest, when the fare is counted, the fact that the mechanism has been tampered with, either through accident or design; and, third, it will prevent the excessive or injurious depression of the slide *B* in any event other than intentional forcible rupture. *E* is an offset upon spring-slide *B*, to which is attached one end of a connecting-rod, *F*, whose other end connects with one end of escape-lever *G*. This escape-lever is pivoted at *g*, and, at its other end, it forms, with escape-wheel *H*, a well-known escapement; and, in combination with the pinion *K*, toothed wheel *L*, coiled spring *M*, dial *N*, and hands *O P*, it constitutes a recording mechanism. The spring *M* is wound up by means of a key, which passes through a hole in the frame of the box in rear of the face of the dial. *R* is a hammer attached to escape-lever *G*, and *S* is a gong placed at a distance from the hammer suited to its stroke. This hammer may be put upon a pivoted or lever handle, one end of which lever may be struck by the escape-lever *G*, instead of the handle being directly secured to the escape-lever, as shown in the drawing. *T T* are plates of glass inserted in suitable parts of the frame of the fare-box. *V V* are fare-chambers, duplicates of each other. Both may be used, or one may be omitted. The sides of these chambers are made to taper pyramidal, as shown in the drawing, in order that there may be room within the fare-box to allow the bottom *V²* of the fare-chamber to slide back and forth, and also in order to concentrate the fare toward the face of the box in a point more directly in line above a point in the final lock-chamber *W*, where, also, it is desired to concentrate the fare. The sliding bottom *V²* may be provided with one spring, as shown in the drawing, or two springs may be used side by side. *D²* is a door adapted to be locked, and provided with a glass plate, *T²*. This door forms the front or one side of the fare-cham-

ber *V*, and, while allowing the interior of the fare-chamber to be seen through its glass plate *T²*, it also permits of access to the interior of the fare-chamber for the purpose of cleaning it. This is an important matter, as the interior of the fare-chamber will collect a great deal of dust, causing the glass plates particularly to become, in a short time, quite opaque. The final lock-chamber *W* has its sides also tapered to angles suited to allow, if desired, the fare-box to be protruded a certain distance through a partition or wall of a car or other conveyance, and yet to discharge the contents of the chamber within the car. *W²* is a hinged or falling bottom of the final lock-chamber *W*. It may be either latched or locked, as shown in Figs. 3 and 6. *X* is an outer door near the bottom of the fare-box, having an offset, *Y*, attached thereto, which folds with the door, and thus closes all access to the falling bottom *V²* when the door is locked.

This offset or bottom *Y* may extend as far under the bottom of the fare-box as practicable, and thus will form a neatly-closed bottom thereto; but I prefer to construct a spout or pipe, *Z*, on the bottom of the fare-box, forming an extension of the box-frame itself, as is seen in Fig. 8, through which all the fare in the lock-chamber will be discharged into a bag or other receptacle held closely around its mouth by an authorized collector. The outer door *X* being locked will prevent all access to the final lock-chamber *W*, for only by opening first the outer door can the falling bottom *V²* be opened, and which, when opened, discharges all the contents of the chamber, so that no part of the fare can be dishonestly abstracted, leaving a portion of it in the chamber, but all the fare will be discharged together. Thus, independently of the recording mechanism, an additional check is imposed against dishonesty. Different keys, if desired, may be fitted to the locks of the door *X* and final lock-chamber *W*, or the chamber may simply have its bottom latched.

L² is a lamp-chamber. This lamp-chamber is so situated that the light from a lamp placed therein is transmitted to the fare-chamber *V* solely by one inclined and perforated reflector, *R²*. The top of the lamp-chamber is formed into or has inserted in it a socket, *S²*, bored out and tapped to receive a pipe screwing into its threads. The pipe and socket are to be of any suitable metal, and they thus form a neat and easily attachable and detachable chimney for the lamp-chamber.

The operation of the parts above mentioned, and of the fare-box as a whole, is as follows: When a coin is inserted in the slotted part of the mouth-piece *A*, it will rest upon the spring-slide *B*, and stand about half-way out of this slot. Upon pressure being applied to the coin by the hand of a depositor sufficient to depress the slide *B*, its springing reaction will trip the coin by pressing it against the edge of the recess *c* in the guide *C*, the edge of the recess thus becoming a fulcrum

for the coin above, and parallel with its diameter. The coin is thus forced out of the slotted part of the mouth-piece A, provision being made for its escape therefrom by the crescent-shaped recess in the mouth-piece A, uniting with the slotted part thereof, and thus forming the complete orifice a. The coin, being thus tripped, is guided by the offset c² upon guide C, and discharged by the further action of spring-slide B into the fare-chamber V below. Here the coin or fare will remain until discharged by the act of an operator, who will withdraw the sliding and self-closing spring-bottom V², by pulling the knob v, when the fare will fall into the next receptacle provided for it.

It will be observed that the spring-slide B, being united to the escape-lever G, when depressed by the insertion of a coin, causes the escape-lever to release one tooth of the escape-wheel H, whereby, through the action of the wound-up spring M and gearing K L, the hands O P register upon the dial N, as in ordinary clock mechanism, every depression of the spring-slide B sufficient, by the reaction of the slide, to trip and discharge a coin. By the return stroke of the escape-lever G, after the discharge of the coin, the hammer R, attached to the escape-lever, is caused to strike the gong, thus announcing the deposit of a fare.

The fare having been dropped through the spring-bottom V² into the final lock-chamber W, the operation of discharging the final lock-chamber is as follows: Being in shape somewhat like a hopper, its contents will quickly be discharged through its falling bottom W², when opened, into the spout or tube Z, from which it is intended that the fare shall be received into a bag placed closely around its mouth, by some person authorized to collect the fare, who will thus quickly and certainly receive the whole contents of the chamber.

The falling bottom W² being closed or locked, and the outer door X, through which only can access be obtained to the bottom W², being also closed and locked, the fares will remain secure from abstraction until again removed, in the manner above mentioned, by some authorized person.

It is obvious that, in place of the recording clock mechanism or escapement herein described, as combined with my fare-receiving mechanism, various other recording mechanisms may be used without departing from the principle of my invention; for instance, among others, a register or counter may be employed, such as is ordinarily used for record-

ing the revolutions of a steam-engine. The mouth-piece A, which constitutes a part of the fare-receiving mechanism, may also have its orifice a enlarged to suit the slide B or guide C, according as either may be made stationary or movable, as hereinbefore mentioned.

Having thus fully described the construction and operation of my invention, above mentioned, what I claim as of my invention in a passenger fare-box is—

1. The combination of a recording mechanism with a slide, B, and a guide, C, whereby the fare is received in the fare-box, and its deposit recorded, substantially in the manner and for the purposes described and set forth.

2. A mouth-piece, A, perforated with an orifice, a, shaped substantially as described, and adapted for the reception of nickel or other coins, or tokens thereof, substantially in the manner and for the purposes described and set forth.

3. The combination of a spring-catch, D, with a spring-slide, B, whereby the motion of the slide is controlled and effected, substantially in the manner and for the purposes described and set forth.

4. The combination of a mouth-piece, A, a spring-slide, B, and a guide, C, whereby a coin is received, guided, and discharged into the fare-box, substantially in the manner and for the purposes described and set forth.

5. The combination of a slide, B, a guide, C, a connecting-rod, F, and an escape-lever, G, whereby a coin is discharged into the fare-box, and motion communicated to any suitable recording clock mechanism, all substantially in the manner and for the purposes described and set forth.

6. The combination of an escape-lever, G, a hammer, R, and any suitable gong, whereby the hammer is caused to strike the gong upon the return stroke of the escape-lever after the deposit of a fare has been made in the fare-box, all substantially in the manner and for the purposes described and set forth.

7. The combination of an outer door, X, with a fare-chamber, W, having tapered sides and a hinged or falling bottom, W², whereby the chamber W is rendered doubly secure, and the whole contents of the chamber necessarily discharged by the falling of its bottom, all substantially in the manner and for the purposes described and set forth.

ARTHUR J. MOXHAM.
